UNITED STATES PATENT OFFICE.

EMIL POHL, OF AUSTIN, PENNSYLVANIA.

COMMINUTING APPARATUS.

Application filed March 10, 1924. Serial No. 698,020.

To all whom it may concern:

Be it known that I, EMIL POHL, a citizen of the United States, residing at Austin, in the county of Potter and State of Pennsylvania, have invented certain new and useful Improvements in Comminuting Apparatus, of which the following is a specification.

My invention has reference to the manufacture of paper, cardboard, and the like, and consists in a new apparatus for comminuting waste particles of wood, such as wood-chips, for utilizing it as a filling material in the manufacture of paper, cardboard and the like. My new apparatus is designed to effectively disintegrate the material under treatment, and is simple both in construction and operation.

In the drawing herewith to illustrate my invention, Fig. 1 is a side elevation partly in section of the new apparatus, the upper portion of the fixed standards being broken away, Fig. 2 is a fragmentary view seen from the left in Fig. 1; Fig. 3 is a similar view seen from the right in Fig. 1; Fig. 4 is a top view; Fig. 5 is a sectional view along line 5—5 in Fig. 2, and Fig. 6 is a sectional view along line 6—6 in Fig. 2.

In describing my invention more in detail, I shall first describe the apparatus for carrying out my new process, with reference to the drawings.

In fixed standards 1, 2 are provided a plurality of sets of cooperating rollers, I, II, III, IV preferably made of stone. These rollers however can also be made of artificial stone, emery, basalt lava, or of metal, such as steel, hard bronze, cast steel, or any other suitable hard material. Each set of rollers comprises a large roller 3 and two smaller rollers 4, 5 adapted to cooperate with 3. The diameter of the large roller 3 relative to the diameter of the smaller rollers 4, 5 is preferably at the ratio of 2:1, while the width of the rollers is about three feet, more or less. The large rollers 3 revolve at slow speed, while the smaller rollers 4, 5, revolve at high speed. The large rollers 3 of all the sets are rotatably journalled in fixed bearings 6, while the smaller rollers 4, 5 are rotatably journalled in adjustable bearings 7, the bearings 7 being mounted on supports 8 and under the

control of helical springs 9, making the bearings 7 yielding. The large rollers 3 are set in slow rotation through a set of meshing gears shown in Figs. 2 and 3 and in broken lines also in the lower half of Fig. 1. The driving pinion 10 is mounted on a shaft 11 (Fig. 4) carrying a fast and loose pulley 12 and 13 respectively over which passes a belt 14. This driving pinion 10 directly meshes with the gear 15 mounted on the projecting outer end of the axis of the bottom roller 3 (Fig. 1). The gear 15 in turn meshes through an intermediate gear 16 with the gear 17 on the axis of the next succeeding large roller 3, and so forth, as clearly shown in Figs. 1-3. The smaller rollers 4, 5 are rotated at a much greater speed than the large rollers 3. To this end, the rollers 4, 5 are driven from a large pulley (not shown) by means of a belt 18 (Fig. 5) which passes around small pulleys 19, 20 mounted on the axes 21, 22 of the smaller rollers 4, 5. Also, a tensioning roller 23 is provided to keep the belt 18 taut and in frictional engagement with the said small pulleys mounted on the axes of the smaller rollers 4, 5.

At the top of the fixed standards 1, 2 is provided the feeding table 24, extending across the entire width of the rollers, and having a transverse slot 25. Downwardly extending projections 26, 27 of the feeding table reach between the uppermost large roller 3 and the top-roller 4 of the uppermost set of smaller rollers 4, 5 forming a feeding chute. Between the top set I of rollers and the next lower set II of rollers is disposed, in fixed position, a chute comprising the cooperating members 28, 29, which have downwardly projecting edges (Fig. 1) extending into the space between the large roller 3 and the smaller rollers 4, 5 of the said set II of rollers. Similar chutes are provided between the second and third sets II and III and between the third and fourth sets III and IV of rollers. Below the bottom set IV of rollers, is provided a discharge chute 30. These chutes may be made of tin, or any suitable inexpensive material.

The rollers used are preferably made of a hard stone, either natural or artificial, or they may be made of emery, or a mixture

containing emery. They also may be made, of course, of any other suitable material, such as metal.

The operation of the apparatus is shortly 5 as follows.

From a vat (not shown) in which the material to be comminuted is kept moving by suitable agitating means, the material mixed with a sufficient amount of water flows onto 10 the slotted feeding table 24 which allows the material to pass through the above mentioned feeding chute to reach the first set (I) of rollers. Here, the material is squeezed under yielding pressure between and past 15 the slowly rotating large roller 3 and the smaller rollers 4, 5 revolving at a higher rate of speed than the roller 3. From the first set I of rollers, the material passes down through the next chute to the second 20 set II of rollers where it is again subjected to the comminuting combined action of the large rollers 3 and the opposing, rapidly revolving smaller rollers 4, 5, and so forth, until the material reaches the outlet or dis- 25 charge chute 30 below the bottom set IV of rollers, through which chute the material passes on to screens to be subjected to further treatment, either wet or dry.

The position of the smaller rollers 4, 5 30 relatively to the larger rollers 3 can be exactly adjusted, an abutment 31 being provided to determine the extreme forward position of the rollers 4, 5 toward the large roller 3. Because of the provision of the helical 35 springs, the smaller rollers are yielding. The rotation of the rollers is indicated by the arrows in Fig. 1, from which it appears that the smaller rollers rotate in opposite direction to their corresponding larger 40 roller.

The smaller rollers are held under yielding pressure being under the control of spring 9. The one end of each spring abuts 45 against an adjustable slide block 32, which can be moved to and fro on the support 8

and is held in its adjusted position by screws 33.

I claim as my invention:

1. In comminuting apparatus, the combination of a plurality of superposed sets of hard smooth rollers rotatably journaled in fixed standards, each set comprising a large roller mounted in fixed bearings and two smaller rollers mounted in movable bearings cooperating with said large roller, means for rotating all said large rollers of the sets at a uniform slow speed in the same direction by means of a train of gears with idler gears interposed between the gears upon the shafts of said large rollers, means for driving the smaller rollers in each set at a higher uniform speed by independent driving means and means for feeding and guiding the material to be treated between the sets and also between the two smaller 65 rollers in each set.

2. In comminuting apparatus, the combination of a plurality of superposed sets of hard smooth rollers rotatably journaled in fixed standards, each set comprising a large roller mounted in fixed bearings and two smaller rollers mounted in movable bearings cooperating with said large roller, means for rotating all said large rollers of the sets at a uniform slow speed in the same 70 direction by means of a train of gears with idler gears interposed between the gears upon the shafts of said large rollers, means for driving the smaller rollers in each set at a higher uniform speed by independent 75 driving means, means for adjusting the pressure of said smaller rollers against said larger roller in each set, means for holding the movable bearings under a yielding pressure relative to the fixed bearings, and means 80 for feeding and guiding the material to be treated between the sets and also between the two smaller rollers in each set.

In testimony whereof I affix my signature.

EMIL PÖHL
